UNITED STATES PATENT OFFICE.

WILLIAM NOREEN, OF MINNEAPOLIS, MINNESOTA.

COMBINATION WRENCH AND PLIERS.

Application filed February 14, 1921. Serial No. 444,784.

To all whom it may concern:

Be it known that I, WILLIAM NOREEN, a citizen of the United States, residing at Minneapolis, in the county of Hennepin and State of Minnesota, have invented certain new and useful Improvements in Combination Wrenches and Pliers; and I do hereby declare the following to be a full, clear, and exact description of the invention, such as will enable others skilled in the art to which it appertains to make and use the same.

My invention provides a simple and highly efficient combination tool adapted for very general use but especially adapted to be carried with an automobile or other vehicle. Primarily, the combination tool includes a wrench and a pair of pliers, but also involves certain other instruments such as a screw-driver and wire cutter. The wrench handle and one arm of the pliers are adapted to be telescoped and locked together so that the combination tool may then be carried or used as a single instrument. When, however, there is occasion for simultaneously using both the wrench and pliers, these two devices may be readily separated and independently used. When the pliers are applied to the wrench, they afford an extension of the wrench handle for use when very considerable power is required.

The preferred form of this improved combination tool is illustrated in the accompanying drawings, wherein like characters indicate like parts throughout the several views.

Referring to the drawings:

Figure 1 is a view partly in plan and partly in horizontal section showing the improved tool with the elements thereof assembled;

Fig. 2 is an edge elevation of the complete tool shown in Fig. 1;

Fig. 3 is a section on line 3—3 of Fig. 1; and

Fig. 4 is a plan view showing the wrench and pliers separated.

The wrench comprises a handle 5 formed rigid or integral with one wrench jaw 6. Mounted for sliding movements on the head of the wrench, toward and from the jaw

6, is a movable jaw 7 adapted to be adjusted by a screw or finger-operated worm 8. This wrench structure proper may be of the usual or any suitable construction, but, as shown, the movable jaw 7 is rigid with a sliding tooth plunger 9, with the threads of which the worm 8 is engaged.

The pair of pliers is made up of substantially the usual plier levers 10 and 11, pivotally connected at 12 and having cooperating jaws formed with serrated pinching surfaces 13 and 14.

As a feature of this invention, the handle 5 of the wrench is made hollow and the plier lever 10 is made with a long straight portion that will freely telescope into the wrench handle 5. As a simple means for detachably holding the plier lever 10 within the handle 5, the former, as shown, is provided with a notch 15 adapted to be engaged by a bulged portion on a flat spring 16 that is secured within the wrench handle. To hold the plier lever 11 against the wrench handle when the two tools are coupled together, I have shown a small U-shaped yoke 17 pivoted to the exterior of the wrench handle and engagable with a notch 18 in said lever 11. Preferably, the lever 11, at its end 19, is formed to afford a screw-driver. Of course, the engagement of the yoke 17 with the notch 18 also assists in holding the two tools, to wit: the wrench and the pliers, coupled together. The pliers are preferably of the type provided with the customary wire-cutting blade portions.

When the two tools are coupled together as shown in Figs. 1 and 2, the head of the pliers can be used as a handle for operating the wrench or the head of the wrench can be used to afford long leverage in operating the pliers. Of course, the two tools thus coupled together can be carried as a single tool. When, as very often happens, it is necessary to use both the wrench and pliers at the same time, as when turning a nut on a bolt, the head of which must be held to prevent rotation of the bolt, the two tools can be quickly separated, as is evident from the foregoing.

What I claim is:

A combination tool comprising two com-

plete tools, one of which tools has pivotally connected levers and the other of which tools has a handle into which one of the levers of the first-noted tool is slidably engageable, means for locking the other lever of said first-noted tool to the handle of said second-noted tool, the levers of said first-

noted tool having co-operating jaws, the two tools being thus connected with the jaws of said first-noted tool projecting and forming an extension of the handle of said second-noted tool.

In testimony whereof I affix my signature.
WILLIAM NOREEN.
